ROTARY DRILLING UNIT

Daniel A. Bennett and August R. Maier, Oil City, Pa., assignors to Oil Well Supply Company, a corporation of New Jersey

Application March 30, 1942, Serial No. 436,908

1 Claim. (Cl. 255—19)

1

This invention relates to improvements in rotary drilling units of the character comprising a rotary and a prime mover directly driving said rotary.

While drilling units of the character stated are generally suitable for their intended purpose, it is sometimes desirable or necessary to provide for auxiliary or emergency drives to or from said unit, as when power failure occurs, either by failure of the prime mover of the drilling unit or of the prime mover of the hoisting apparatus of the drilling rig. Various means have been provided heretofore for such purposes, but the same have certain disadvantages as hereinafter pointed out.

For example, separate auxiliary sprockets and chains have been provided for emergency drives to and from the drilling unit, together with clutches and the like for engaging said drives. While such devices will effect the ultimate result desired, they are cumbersome and expensive, and generally involve considerable delay in connecting and disconnecting the same. Further, they must be driven at all times, including the greater intervals when they are not being used for auxiliary or emergency purposes, producing unnecessary wear and power cost, and presenting a constant hazard and source of injury to men and apparatus.

The principal object of our invention is to eliminate the complexity and numerous parts of such auxiliary or emergency drives to enable efficient and immediate power transmission to or from the drilling unit when desired.

Our invention contemplates the employment of a single auxiliary or emergency drive connection between the drilling unit and other powered apparatus, as for example, a hoisting unit, which drive will remain inactive when not in transmission of power, but which may be instantly engaged or disengaged when desired.

Additional objects and advantages will become apparent from the following description taken in connection with the accompanying drawings, wherein:

Fig. 1 is a plan view of a rotary well drilling apparatus including a drilling unit embodying our invention;

Fig. 2 is an enlarged sectional view taken on the line II—II of Fig. 1; and

Figs. 3, 4 and 5 are diagrammatic views illustrating the three operating conditions provided by our invention.

Referring to the drawings, Fig. 1 illustrates a rotary well drilling rig including a drilling unit A and a hoisting unit B, the latter being powered

2 by a prime mover C connected to the jack shaft 2 of the hoist as by means of a belt drive 3 and driving a slush pump D through a belt drive 4. The hoisting unit B includes a rotary drive shaft 5, line shaft 6 and drum shaft 7. The rotary drive shaft 5 may be driven from the jack shaft 2 by a driving connection 8, and line shaft 6 may be driven from said jack shaft by drive 9, the line shaft driving the drum shaft through a connecting drive 10. The said interconnecting drives of the hoisting unit are diagrammatically illustrated, since such drives are well known and understood in the art.

The drilling unit A is mounted upon a pair of skids or supports 11, and includes a prime mover E connected with and driving the rotary R. The present invention has to do with the provision of an auxiliary or emergency driving means for said drilling unit, whereby a separate drive or power transmission is provided to or from the drilling unit. The rotary shaft 12 is connected with the prime mover E through a reduction gear F, as when employing an internal combustion engine for said prime mover, in which case the power 25 of the engine E is transmitted through a torque converter, diagrammatically indicated at T. The transmission connecting means or shafting between the prime mover and the rotary shaft 12 is interrupted at two spaced intervals, at which 30 intervals, suitable separable couplings 13 and 14 are provided. Said couplings are preferably of the type providing for shaft misalignment and possessing the capacity to be quickly engaged and disengaged. For example, couplings of the cut-out type may be employed, one of which is shown in detail in Fig. 2.

The couplings as shown each include a gear element 15 secured to one shaft, as the rotary shaft 12 in coupling 13, and a similar gear element 16 is keyed to the connecting shaft 17, the latter shaft being separate from the rotary shaft and forming a connecting element with the prime mover E through the reduction gear F. A housing 18 encloses the gear elements 15 and 16 of the coupling, said housing including internal gear portions 19 adapted to mesh with the said gear elements when the coupling is in connecting or transmitting position, which position is shown in full lines in Fig. 2.

50 To disengage the said coupling the housing 18 is moved longitudinally to the left in Fig. 2, thereby disengaging the gear elements 15 and 16, and preventing transmission of power between the shafts 12 and 17. A set screw 20 is mounted 55 in the housing 18 and extends into cooperative

position with respect to an annular collar 21 on the gear element 15, said set screw functioning to retain the coupling in engaged or disengaged position by preventing longitudinal movement of the housing with respect to said annular portion and the gear elements from one position to the other, it only being necessary to withdraw said set screw out of interfering position with the annular portion 21 in order to actuate the coupling in the manner described.

While shifting means may be connected with the housing 18 if desired, the housing is readily and easily slidable in relation to the gear elements 15 and 16, so that the same may be moved by hand when actuating the coupling to engaged or disengaged position.

Mounted on the shafting between the couplings 13 and 14, we provide an auxiliary drive means including a spline collar 22 secured to the connecting shaft 17, and a sprocket or drive member 23 freely rotatable on said shaft, said sprocket having an internal spline portion 24 adapted to engage the spline collar 22. A shifting collar 25 is provided for the sprocket 23, said collar being actuated by a shifting lever 26 mounted on the drilling unit.

Sprocket or drive means 23 may be connected by a chain 27 with the hoisting unit B, as by means of a dual idler sprocket 28 freely rotatable on the drum shaft 7 of said unit, the dual sprocket 28 being connected with the rotary drive shaft 5 by a chain drive 29, whereby the power of either the drilling or hoisting units may be interchangeable for auxiliary or emergency driving purposes.

The operation of our invention is illustrated in Figs. 3, 4 and 5. Fig. 3 illustrates the position of the mechanism when operating the drilling unit A in the conventional manner to drive the rotary R by means of the prime mover E, couplings 13 and 14 being in engaged or transmitting position, and sprocket 23 being free upon the shaft 17. In such position, the rotary is driven without the transmission of power or motion to the single auxiliary or emergency drive sprocket 23 and chain 27.

Fig. 4 shows the apparatus in position for auxiliary or emergency drive to the hoisting unit, in which case, the coupling 13 is disengaged, thereby disconnecting the rotary R from its prime mover

E. The sprocket 23 is shifted to engage the spline 22-24, whereupon the sprocket 23 and its chain 27 are driven from the prime mover E to drive the rotary drive shaft 5, from whence the power may be transmitted to and from the hoisting unit in accordance with the transmission facilities of that unit.

Fig. 5 illustrates the operation of our invention for an auxiliary or emergency drive from the hoisting unit or other powered external means to the rotary. For such operation, the coupling 13 is in engaged or transmitting position and sprocket 23 is connected to its shaft by the spline means 22-24, with coupling 14 in disengaged or non-transmitting position, whereby the power applied to chain drive 27-23 by the hoisting unit, is transmitted directly to the rotary R.

Hence, it will be seen that we have provided a simple and efficient auxiliary or emergency drive to or from the drilling unit, employing a single auxiliary driving connection between said drilling unit and another power unit, which connecting drive remains inactive during the operation of either or both of said units in their conventional manner. The structure so provided is both simple and durable, the parts of said auxiliary drive remaining inactive during the greater periods of time when the drilling and hoisting units are being operated separately, thereby saving in power cost and wear upon the parts of the mechanism, and materially reducing the hazard of injury to men and apparatus.

Various modifications and changes are contemplated within the scope of the following claim.

35 We claim:

In a rotary drilling unit, the combination with a rotary, of a prime mover therefor, connecting shafting between said rotary and prime mover, and an auxiliary drive for the transmission of power to and from the unit comprising a pair of spaced couplings disposed in said connecting shafting and adapted to separately interrupt the transmission of power from the prime mover to the rotary, a transmission member freely rotatable on the portion of said connecting shafting between said couplings, and means for selectively connecting the transmission member to said portion of the connecting shafting.

DANIEL A. BENNETT.
AUGUST R. MAIER.
